UNITED STATES PATENT OFFICE.

LUTHER J. ISENHOUR, OF INDIANAPOLIS, INDIANA.

INCUBATOR AND BROODER.

1,106,451.

Specification of Letters Patent. Patented Aug. 11, 1914.

Original application filed July 17, 1911, Serial No. 638,994. Divided and this application filed April 22, 1912. Serial No. 692,400.

To all whom it may concern:

Be it known that I, LUTHER J. ISENHOUR, a citizen of the United States, residing at Indianapolis, in the county of Marion and

5 State of Indiana, have invented a new and useful Incubator and Brooder, of which the following is a specification, reference being had to the accompanying drawings, and to the letters and figures of reference marked 10 thereon.

This invention relates to the type of incubator or brooder that is adapted to be transferred from place to place in order to be hygienic, the invention having reference 15 more particularly to the heating apparatus and to the heat controlling appliance thereof, more especially the improvements described in my pending application for Letters Patent of the United States filed July 20 17, 1911, Serial No. 638,994, of which this is a divisional application for Letters Patent.

The object of the invention is to provide simple and reliable heating and heat-controlling apparatus for incubators, brooders 25 or hovers, that shall be so constructed as to not be liable to derangement while being shipped from the factory or when roughly handled by the user.

A further object of the invention is to 30 provide advantageous, cheaply constructed and durable and economical apparatus of the above mentioned character.

The objects of the invention are attained in the structure illustrated in the accompanying drawings and hereinafter particularly described and claimed.

Referring to the drawings, Figure 1 is a front elevation of an incubator and brooder having the invention applied thereto; Fig. 40 2, a perspective view of a part of the heat regulator inverted; Fig. 3, a horizontal section approximately on the line A A in Fig. 1; Fig. 4, a fragmentary sectional perspective view of an improved heat radiator; Fig. 45 5, a fragmentary sectional elevation of parts of the heat regulator; Fig. 6, a vertical section on the line B B in Fig. 3; Fig. 7, a fragmentary section reproducing portions of Fig. 6 on an enlarged scale; Fig. 8, a fragmentary inverted plan of the heat regulating apparatus; Fig. 9, a fragmentary perspective view of internal parts of the apparatus, and Fig. 10, a fragmentary sectional elevation approximately on the line C C in Fig. 3.

55 In the different figures of the drawings

like elements or features of construction are indicated by corresponding reference characters.

The incubator or brooder includes a housing or inclosure comprising a cylindrical metallic wall 1 that is provided on its inner side with an annular ledge 2 arranged somewhat above the normally lower end of the wall, the wall being provided with a lining 3 at the inner side thereof that extends from the ledge down to the lower end of the wall, the lining preferably being removable and composed of suitable material that is a non-conductor of heat. The lower portion of the wall is provided with a suitably curtained door-way 4. An apertured or open work elevated floor 5 is secured upon ledge 2, a centrally arranged guide-ring 6 being secured upon the floor and extending about an opening in the floor, and a trap-door 7 is removably seated in the guide-ring 6. The guide-ring 6 is provided on its outer side with a socket 8 in which a supporting stem 9 is rotatively mounted and supports a thermometer 10 in inclined position both longitudinally and transversely, in order that the thermometer may be readily adjusted so as to be clearly visible in the best light afforded through the cover of the housing. An annular inner wall 11, composed of sheet-metal, is secured upon the floor 5 concentrically with the wall 1 and it has an inner lining 12 composed of suitable heat-insulating material. Preferably an annular shield 13 is secured to the under side of the floor 5 and extends downward a suitable distance immediately under the wall 11. The wall 1 is provided with a lining 14 that extends from the floor 5 upward to the upper end of the wall and may be composed of any suitable material that is a non-conductor of heat.

A heat radiator comprises a hollow annular water chamber formed of an outer wall 15, an inner wall 16, a narrow bottom 17 and a narrow top 18, the side walls being spaced a relatively short distance apart, and the outer wall of the radiator is placed against the inner side of the lining 14 so as to prevent outward radiation of heat. The 100 radiator is connected with the wall 1 by means of a supporting pin 19 and is otherwise supported, as will become apparent. A radiating tube 20 is connected with diametrically opposite portions of the radiator 110

and extends above the top of the wall 11, one end of the tube being secured to the wall 16 so that it is in communication with the interior of the radiator, the opposite end portion of the tube extending through both walls of the radiator and is secured thereto, the tube constituting a feed duct. A return duct 21 is arranged under the outer portion of the tube 20 and is secured to the wall 15 of the radiator so that communication is afforded with the lower portion of the interior of the radiator. A brace 22 is preferably secured to the wall 1 and the duct 21. The tube 20 and duct 21 extend through the wall 1 and its lining 14 and have a suitable boiler or heater 23 connected to their outer ends, the heater being provided with a valve or damper 24 having a controlling stem 25. A lamp comprising a reservoir 26 and a burner 27 is placed below the heater or boiler for heating the circulating water therein.

The cover of the housing comprises a disk 28 having a central aperture 29 therein that is closed by a glass plate 30 through which to observe the thermometer 10, the latter being so arranged that it is not obscured by the tube 20. The cover has a suitable lining 31 and normally rests removably upon the wall 1 and the heat radiator. The cover preferably is provided with metallic clips 32 which secure both the lining and the glass plate or window to the cover part 28, the latter having a flange 33 thereon that extends down over the upper portion of the wall 1.

A metallic bracket 34 is secured to the inner lower portion of the wall 1 where the latter is not materially affected by changes of temperature, and it has a pillar 35 formed integrally thereon and extending upward through the floor 5, the upper portion of the pillar having a plug 36 secured therein. A suitable thermostatic device is provided for automatically regulating the heat in the housing and it preferably comprises a corrugated disk 37 provided with a supporting stem 38 which is screwed into the plug 36, a disk 39 secured to the disk 37, and two similar disks 40 and 41 secured together, the disk 40 being secured to the disk 39 and the uppermost disk 41 having a central bearing projection 42 thereon. A tubular journal-bearing 43 extends through and is secured to the walls 15 and 16 of the radiator, the journal-bearing extending through the water space of the radiator and also through the walls 1 and 11 and their linings, and it supports a rock shaft 44 which extends therethrough and has a crank arm 45 on its inner end provided with a crank handle or pin 46 that extends onto the projection 42. The wall 1 has a slot 47 therein to receive the journal-bearing 43 and is closed by a plate 48. An arm head is provided whereby to regulate the valve 30, and it preferably comprises two side plates 49 and 49' secured to the outer

end of the shaft 44, and an integral top 50, and preferably also a bottom portion 51 at one end thereof. An arm 52 is arranged between the side plates 49 and 49' and extends above the shaft 44 and the bottom portion 51 toward the opposite end portions of the side plates, and it has a crook 53 thereon from which extends a return portion 54 provided with a collar 55 which rotatably embraces the shaft 44 beneath the main portion of the arm 52, said arm extending to the operating stem 31 and having an eye 56 thereon connected to a similar eye with which the stem is provided. An adjusting screw 57 is inserted in the top 50 of the arm head and is in contact with the arm 52 for adjusting the arm relative to the arm head, another adjusting screw 58 preferably being inserted in the bottom portion 51 and extending into contact with the opposite side of the arm 52 for assisting to hold the arm firmly in adjusted position, and it will be understood that in some cases either one of the adjusting screws may be omitted. The arm head extends rearward from the valve 30 beyond the shaft 44 so as to partially counterbalance the valve and its operating arm 52.

In practical use the cover is removed from the housing and eggs are placed upon the floor 5, after which the cover is replaced. The heating lamp being put in operation may be regulated at will so as to heat the water which previously has been put into the heater and the radiator. The attendant may look through the glass plate 30 and observe the thermometer in order to ascertain the temperature near the eggs, and if desirable either the lamp burner may be readjusted, or the valve or damper 24 may be readjusted by means of the screws 57 and 58 so as to change the position of the valve relative to the heater to control the current of heat through the heater. Having obtained the required temperature for incubating purposes the temperature is automatically further regulated by means of the thermostatic device actuating the rock-shaft 44 and the arm 52, but in some cases readjustment of the arm relative to the head may be required and can be accomplished without disturbing the temperature in the incubator. The lower portion of the housing below the floor 5 conveniently serves the purpose of a brooder or hover in caring for the little chicks and protecting them from the external climatic conditions, the door-way permitting them to pass out and return at pleasure. The incubator as will be understood may be used either upon a table or floor, or upon the ground, being more desirable on the ground in order that the chicks may have opportunity to scratch in the earth.

Having thus described the invention, what is claimed as new, is—

1. An incubator and brooder including an

- inclosing wall having a slot in its top, a supporting device fixedly supported on the inner side of the wall, a journal-bearing fixedly secured to the supporting device and 5 extending through the slot, a heater on the outer side of the wall, a regulating valve on the heater, a rock-shaft rotatably mounted in the journal-bearing, an arm adjusting head fixedly secured to the outer end of the 10 rock-shaft, an adjusting screw mounted in the head, an arm adjustably connected with the head to be adjusted by the screw relative to the head, the arm being connected with the valve, a crank arm fixed on the inner end of the shaft, and a thermostatic device supported by the wall in contact with the crank arm. 15
2. An incubator including an inclosing wall having a slot in the top thereof, a heater supported on the outer side of the wall, a regulating valve on the heater, a floor supported on the inner side of the wall, an inner wall on the floor spaced from the outer wall, a supporting device fixedly supported between the two walls by the inclosing wall, a thermostatic device supported above the floor adjacent to the inner side of the inner wall, a journal-bearing fixedly secured to the supporting device and extending through the two walls, a shaft rotatively mounted in the journal-bearing, a crank arm fixed on the shaft in contact with the thermostatic device, an arm head fixedly secured to the outer end of the shaft and provided with an adjusting screw, and a controlling arm pivotally connected to the outer end portion of the shaft within the head and in contact with the screw, the controlling arm being connected with the regulating valve. 25
3. In an incubator, the combination of an inclosing wall, a heater exterior to the wall, a regulating valve for the heater, a thermostatic device supported by the inner side of the wall, a journal-bearing fixedly supported and extending through the wall, a rock-shaft mounted in the journal-bearing and having a crank arm thereon extending to the thermostatic device, an arm head comprising a side plate and a top plate, the head being fixedly secured to the rock-shaft, said side plate being vertical, an adjusting screw mounted in the top plate of said head and extending adjacent to the side plate at 35 a distance from the rock-shaft, and a controlling arm pivoted to the rock-shaft adjacent to said side plate and extending in contact with said screw, the controlling arm being connected with the regulating valve. 40
4. In an incubator, the combination of an inclosing wall, a heater exterior to the wall, a regulating valve for the heater, a thermostatic device supported by the inner side of the wall, a journal-bearing fixedly supported and extending through the wall, a rock- 45
- shaft mounted in the journal-bearing and having a crank thereon in contact with the thermostatic device, an arm head fixedly secured to the rock-shaft and comprising a vertical side plate and a lateral bottom plate, 50 an adjusting screw mounted in said bottom plate and extending adjacent to said side plate, and a controlling arm pivoted to said rock-shaft in contact with said screw, the controlling arm being connected with the regulating valve. 55
5. In an incubator, the combination of an inclosing wall, a heater supported exteriorly to the wall, a thermostatic device supported in proximity to the inner side of the wall, a regulating valve for the heater, a journal-bearing fixedly supported adjacent to the inner side of the wall and extending through the wall, a rock-shaft mounted in the journal-bearing and having a crank arm thereon in contact with the thermostatic device, an arm head fixedly secured to the outer end portion of the rock-shaft and comprising two vertical side plates spaced apart and a transverse plate connected to the side plates, 60 an adjusting screw mounted in the transverse plate, and a controlling arm adjustably connected with the two side plates to be guided thereby, the controlling arm being connected with the regulating valve and 65 extending into contact with the screw. 70
6. An incubator and brooder including an inclosing wall, a heater exterior to the wall, a regulating valve for the heater, a thermostatic device supported by the inner side of the wall, a supported journal-bearing extending through the wall, a rock-shaft mounted in the journal-bearing and having a crank arm on the inner end thereof in contact with the thermostatic device, an arm head comprising two side plates and a top plate and also a bottom plate, the side plates being secured to the rock-shaft, a controlling arm pivotally connected to the rock-shaft between the side plates of the head and connected to the valve, and an adjusting screw mounted in the head in supporting contact with the controlling arm. 75
7. In an incubator, the combination of an inclosing wall, a heater exterior to the wall, a thermostatic device supported in proximity to the inner side of the wall, a regulating valve for the heater, a tubular journal-bearing supported in and extending through the wall, a rock-shaft mounted in the journal-bearing and having a crank arm on the inner end thereof in contact with the thermostatic device, an arm head comprising two side plates and a top plate and also a bottom plate, the side plates being fixedly secured relatively near one end thereof to the outer end of the rock-shaft, an adjusting screw mounted in the bottom plate of the head relatively near to said end of the side plates, an adjusting screw mounted in said 80 85 90 95 100 105 110 115 120 125 130

top plate relatively near to the opposite end of said side plates, and a controlling arm extending between said side plates and between said adjusting screws in contact with the screws and having a portion doubled under and extending back to said rock-shaft and pivotally connected therewith, said controlling arm being connected with said valve.

8. In an incubator, the combination of an inclosing wall, a thermostatic device supported at a distance from the inner side of the inclosing wall, a tubular journal-bearing fixedly supported and extending through the inclosing wall, a rock-shaft rotatably mounted in the journal-bearing and having a crank-arm on the inner end thereof in contact with the thermostatic device, a heater

exterior to the inclosing wall, a regulating valve for the heater, an arm head comprising a side plate secured rigidly to the rock-shaft and a top plate extending laterally from the side plate, an adjusting screw mounted in the top plate, and an arm pivoted between its ends to the rock-shaft, one end of the arm being connected to the valve, the opposite end of the arm extending under and in contact with the screw.

In testimony whereof, I affix my signature in presence of two witnesses.

LUTHER J. ISENHOUR.
